UNITED STATES PATENT OFFICE.

VICTOR E. CLARK, OF GRAND RAPIDS, MICHIGAN.

BROOM.

1,377,560.

Specification of Letters Patent. Patented May 10, 1921.

Application filed September 3, 1918. Serial No. 252,428.

To all whom it may concern:

Be it known that I, VICTOR E. CLARK, a citizen of the United States of America, residing at Grand Rapids, in the county of Kent and State of Michigan, have invented certain new and useful Improvements in Brooms; and I do hereby declare the following to be a full, clear, and exact description of the invention, such as will enable others skilled in the art to which it appertains to make and use the same.

This invention relates to improvements in brooms and is more particularly concerned with brooms having a separable brush and clamping head parts, such as shown and described in my Patent #1,015,263 issued January 16, 1912. It is an object and purpose of the present invention to improve the same by providing a broom simple in construction and compact in arrangement; to provide a construction in which the upper end of the brush does not need to be trimmed for fitting in the clamping members, and to further provide the device with many new and useful features of construction and arrangements of parts as will more fully appear as the description of a preferred form of the invention progresses, reference being had to the accompanying drawing showing the same, in which—

Figure 1 is a perspective view of a broom showing my invention, the parts being in assembled position.

Fig. 2 is a fragmentary vertical section through the same.

Fig. 3 is a perspective view of a clamping head opened and removed from the brush and handle, and

Fig. 4 is a perspective view of the upper portions of the separable brush members.

Like reference characters refer to like parts in the various views of the drawing.

The head or clamp of the broom is composed of two opposing members 1 substantially alike and stamped from sheet metal and pivotally connected to each other, each being provided near its upper portion with a half ferrule 2 formed integral with the body portions of the clamping members 1. Each body portion is adapted to engage one side of the upper end of the brush, indicated at 3. The half ferrules 2 are formed with laterally extending ears adapted to overlap so that the clamping members may be pivotally connected together at the upper ends of the ferrules by rivets or otherwise, as in-

dicated at 2^a. The brush is formed of suitable broom material sewed together in the usual manner and adjacent its upper end, a metallic band 4 surrounds the same binding the upper ends of the strands of broom material tightly together. The clamping members each at its lower edge is turned inwardly, as indicated at 5, to provide flanges to pass underneath this band when the clamp is applied to the broom.

Each member is also provided with a loop 6 projecting inwardly from the same, being struck from the body of the metal, as shown. The loops are adapted to overlap each other when the clamp is closed and serve as opposing half nuts to oppositely engage the tapered threaded end 7^a of the handle 7 which is inserted through the ferrule members 2 and the overlapping loops 6, threading 75 therein as far as desired.

The brush is provided with a recess 8 in its upper end in which the loops 6 may seat, thus permitting the upper end of the brush to engage the inner sides of the upper portions of the clamping members and the corners of the brush are rounded to fit the tops of the clamp. The upper end of the brush in the center of the recess 8 is also provided with an opening 8^a to receive the tapered end 7^a of the handle 7 which must enter the brush as it is screwed into place through the loops 6.

Each clamping member 1 adjacent each end and directly above the inturned portions 5 has a portion struck inwardly making lugs 9, the same being adapted to pass alongside of the inwardly pressed portions of the broom material above the band 4, so that the lower ends thereof come directly above the band 4, as shown best in Fig. 2, this, in connection with the inturned portions 5, locking the brush against movement with respect to the clamping members when the handle has been threaded into place.

It will be seen that this device is very simple in construction, the clamp being composed of two members which are identical so that the same may be formed by the same set of dies arranged in opposed position 105 and pivotally connected at their upper portions as described. The brush 3 is readily detachable from the head for the purpose of replacing it with a new one, the operation consisting of merely removing the handle 110 and separating the lower edges of the clamping members sufficient to remove one brush.

member and insert another, after which the clamping members are closed by threading the handle into place. This construction is also of value in that sufficient space is provided to receive the upper portion of the brush above the band 4 without the necessity of trimming the same at the sides as previously necessary in similar constructions. When the handle 7 is inserted through the ferrules 2, and through the overlapping loops 6 and screwed into place, it will, by virtue of its taper, bring the sides of the clamping members tightly against the surface of the brush with the band 4 disposed between the lower ends of the lugs 9 and the inturned portions 5 of the clamping members. The insertion of the point of the handle into the end of the brush not only serves to stiffen the connection between the handle and brush, but also wedges the material of the upper end of the brush apart, pressing it against the band and thus more firmly clamping the parts together. The lower end of the handle may be provided with a metallic threaded sleeve to take the wear against the inner edges of the loops 6 if desired.

I claim:

1. A broom comprising a brush, an outwardly projecting band rigidly secured to the brush, a clamp consisting of two substantially similar parts each provided with an inturned portion at the bottom to pass below the band, opposing half-ferrules at the top of the clamp to embrace the handle, inwardly projecting overlapping loops on the respective parts of the clamp to receive the handle, a handle extending downward between the half-ferrules and having a tapered screw-threaded end oppositely engaging the loops and extending into the brush and below the plane of the band, and lugs struck inwardly from each part of the

clamp directly over said band, substantially as described.

2. A broom comprising a brush having a central recess at the top, an outwardly projecting band surrounding the brush and rigidly secured thereto, a clamp consisting of two substantially similar parts, half-ferrules at the top of the clamp pivoted to each other, each part of said clamp being also provided at its lower end with inturned portions to pass below the band, inwardly projecting and overlapping loops on the respective parts of the clamp extending within the recess in the brush, a handle extending through the semi-ferrules and having a tapered screw-threaded end extending through the loops and oppositely engaged thereby, and thence extending into the brush and below the plane of the band whereby the clamp is tightened inward and the brush spread outward within the band, and a lug on each clamp part adjacent each end thereof extending downwardly and inwardly, the lower ends thereof coming immediately above the band, substantially as described.

3. A broom comprising a handle, a brush provided with an outer projecting band rigid with the brush, a clamp consisting of two parts or members pivoted together at opposite sides of the handle and adapted to swing inwardly and outwardly and having inwardly extending flanges to engage beneath the said band, said parts or members being also provided with inwardly extending lugs spaced from the said flanges and arranged to engage over the band and means for holding the said parts or members firmly in engagement with the band and brush.

In testimony whereof I affix my signature.

VICTOR E. CLARK.
